CLAIM

The ornamental design for a combination fan blade cage and motor housing, as shown and described.

DESCRIPTION

FIG. 1 is a perspective view of the combination fan blade cage and motor housing.

FIG. 2 is a front elevational view of the combination fan blade cage and motor housing.

FIG. 3 is a side elevational view of the combination fan blade cage and motor housing.

FIG. 4 is a rear elevational view of the combination fan blade cage and motor housing.

FIG. 5 is a side elevational view (opposite the side elevational view of FIG. 3) of the combination fan blade cage and motor housing.

FIG. 6 is a top plan view of the combination fan blade cage and motor housing.

FIG. 7 is a bottom plan view of the combination fan blade cage and motor housing; and,

FIG. 8 is a cross-sectional view of the fan blade cage portion of the design taken along line 8—8 in FIG. 1.

The broken line showing of environmental structure in FIGS. 1—8 is for illustrative purposes only and forms no part of the claimed design.

1 Claim, 8 Drawing Sheets
